POULTRY FEEDER

Dewey H. Hill, Kokomo, Ind., assignor to Globe American Corporation, Kokomo, Ind., a corporation

Application December 29, 1934, Serial No. 759,685

3 Claims. (Cl. 119—61)

This invention relates to an adjustable support for a chicken feed or watering trough which is particularly applicable for use during the growing period of young chicks.

5 The purpose of the invention is to provide a simple and economical device comprising a pair of end supporting legs, preferably formed of wire, for supporting the ends of the trough in spaced relation to the ground and permitting its adjustment to various heights, depending upon the size of the chicks or chickens to be fed or watered thereby. Convenience in adjustment of the height by the legs, as well as economy of construction, are the features of the invention, as hereinafter more specifically set forth and described.

Other objects and features of the invention will be understood from the accompanying drawing and the following description and claims:

20 Fig. 1 is a side elevation of the trough supported by the adjustable legs with the central portion broken away. Fig. 2 is a perspective view of an end portion of the trough with the legs adjusted to its lowest position. Fig. 3 is an end elevation of the trough with the legs pulled out of locking engagement ready for adjustment to the highest position, illustrated in dotted lines.

25 In the drawing there is illustrated a feeding trough for baby chicks or chickens, such as is commonly formed of galvanized iron or the like, said trough having side walls 10, a bottom 11 and end walls 12. The end walls extend upwardly to support an upper reel 13 which extends longitudinally of the trough thereabove and which is adjustable to position by engagement of a pin 14 in holes 15.

30 The side walls of the trough overlap or extend beyond the end walls to provide flanges 16 in which there are provided a plurality of apertures 17. Said apertures are spaced one above the other in the side walls immediately beyond the end walls 12.

35 Each end wall is provided with a socket comprising a metal strap 18 for receiving a U-shaped bend 19 formed by bending upwardly the intermediate portion of the wire legs 20. Said U-shaped bend or intermediate projection of the legs is frictionally and slidably held by the socket 18 against the surface of the end wall and protrudes through an aperture formed in the flange 16 extending from the bottom 11 of the trough.

40 The wire legs 20 are bent downwardly and laterally from the U-shaped bend 19 to form

supports for the trough at their lowermost extremities, and then are bent upwardly and inwardly to provide portions 21 with inwardly extending ends 22 adapted to engage in and extend through the apertures 17 of the side wall flanges 16.

45 By reason of the flexibility of the wire legs 20, adjustment of the position thereof with respect to the trough for varying its height from the ground may be had by manually and forcibly bending the portions 21 laterally away from the side walls and against the inherent spring tension of said legs to remove the ends 22 from their respective apertures. Upon the legs being thus unlocked, they may be moved up or down with respect to the end of the trough through the frictional sliding action of the U-shaped portion 19 in respect to the socket 18 and aperture in the flange of the bottom 11, as illustrated in Fig. 3.

The invention claimed is:

1. In combination with a feeding trough, supporting legs formed of wire adjustably associated with each end thereof, said trough being provided with a plurality of spaced apertures, sockets formed on the end walls of said trough, and intermediate vertical extensions extending upwardly from said legs slidably extending into said sockets, the opposite free ends of said legs being adapted to engage in said apertures for locking said legs in adjusted position in respect to said trough.

2. In combination with a feeding trough, sockets formed on at least two of the walls thereof, said trough having series of spaced apertures therein, and a pair of legs adjustably mounted with respect to each of said walls for varying the supporting height of said trough, each of said pairs of legs being formed of wire and bent with an upwardly extending U-shaped intermediate portion slidably extending into one of said sockets and the free ends of said wire legs extending upwardly and inwardly to extend into and interlock with said apertures.

3. In combination with a feeding trough, supporting legs formed of wire adjustably associated therewith, said trough being provided with a plurality of spaced apertures, sockets formed on at least two of the walls of said trough, and intermediate vertical extensions provided on said legs adapted to slidably extend into said sockets, the opposite free ends of said legs being adapted to engage in said apertures for locking said legs in adjusted position with respect to said trough.
